(57) **CLAIM**

The ornamental design for a pivot pin tool, as shown and described.

DESCRIPTION

FIG. 1 is a front perspective view of a pivot pin tool showing my new design;

FIG. 2 is a left side view of the pivot pin tool;

FIG. 3 is a front view of the pivot pin tool;

FIG. 4 is a top view of the pivot pin tool;

FIG. 5 is a rear view of the pivot pin tool;

FIG. 6 is a bottom view of the pivot pin tool;

FIG. 7 is a front perspective view of the pivot pin tool;

FIG. 8 is a right side perspective view of the pivot pin tool;
and,

FIG. 9 is a right side view of the pivot pin tool.

The broken lines of the pivot pin tool depict parts of the pivot pin tool that form no part of the claimed design.
